Patented Nov. 5, 1918.

UNITED STATES PATENT OFFICE.

WILLIAM A. STAFFELDT, OF READING, MICHIGAN.

FOUNTAIN-PEN.

1,283,944.

Specification of Letters Patent.

Patented Nov. 5, 1918.

Application filed April 1, 1918. Serial No. 226,068.

To all whom it may concern:

Be it known that I, WILLIAM A. STAFFELDT, a citizen of the United States, and a resident of Reading, in the county of Hillsdale and State of Michigan, have invented a certain new and useful Improvement in Fountain-Pens, of which the following is a specification.

This invention relates to fountain pens, and the primary object of the invention is to provide a spring controlled resilient obstruction which is automatically forced into the feed duct of the pen when the cap is mounted over the head of the pen for effectively cutting off the flow of ink to the point and prevent leakage of the ink out of the pen when the latter is not in use.

More specifically, the object of the invention is to provide a fountain pen in which the feed bar is provided with a resilient portion which is forced into the feed duct to form an obstruction therefor when the cap is mounted over the head of the pen and further to provide a flat spring structure which carries a pin for forcing the resilient portion of the feed bar into the feed duct, which spring moves outwardly, carrying the pin therewith upon the removal of the cap to permit ink to flow through the feed duct.

Further objects of this invention will appear in the following detailed description, taken in connection with the accompanying drawing forming a part of this specification, and in which drawing:

Figure 1 is a fragmentary section through the improved fountain pen with the cap removed and showing no obstruction of the feed duct.

Fig. 2 is a fragmentary section through the pen showing the cap in place and also showing the obstruction in an obstructing position.

Fig. 3 is a side elevation of the feed bar of the pen.

Fig. 4 is a detail perspective view of the resilient obstruction which forms a part of the feed bar.

Fig. 5 is a detail perspective of the spring which controls the operation of the obstruction.

Fig. 6 is a fragmentary sectional view through the spring illustrating the manner of connecting the obstruction engaging pin to the spring.

Referring more particularly to the draw-

ing, 1 designates the barrel of the fountain pen which has the usual type of reduced head 2 which carries the feed bar 3 for feeding the ink from the interior of the barrel 1 to the point 4 of the pen. The feed bar 3 is provided with a feed duct 5 which curves upwardly near the outer end of the feed bar and engages the inner concaved surface of the pen 4.

The feed bar 3 is composed of a main body 6 and a resilient portion 7. The resilient portion 7 comprises a relatively long tongue 8, the outer free end of which has its under surface curved as shown at 9 to 65 form the upper wall of the curved forward end of the feed duct 5 and a relatively large attaching head 10 which is attached in any suitable manner to the main body 6 of the feed bar 3.

The head 2 of the barrel 1 of the pen is provided with an annular bead or enlargement 11 formed at its outer terminal which is recessed as shown at 12 to receive the lower horizontal end 13 of a flat spring 14. 70 The flat spring 14 is attached by means of a suitable bolt or rivet 15 to the head 2 and it extends longitudinally of the head having a curved or bowed portion 16 which is curved to conform to the curvature of the 75 annular enlargement 11. A pin 17 is carried by the bowed portion 16 of the flat spring 14, and it is provided with a substantially frusto-conical head 18 which is connected to the main body of the pin by 80 a relatively small neck 19. The spring 16 is down-struck as shown at 20 for engagement with the neck 19, so as to support the pin 17 by the spring 14 in such manner as to allow 85 compensating movement of the pin under 90 either inward or outward movement of the flat spring.

The pin 17 projects downwardly through an opening in the annular enlargement 11 and through an opening formed in the pen 100 point 4, having its lower inner end rounded and engaging the upper surface of the resilient tongue 8 near the outer free end of the same.

The substantially horizontal end 14' of 105 the spring 14 rides in the recess 12 and guides the movement of the spring 14.

The cap 21 of the pen is provided with an inclined portion 22 formed therein, which inclined portion is provided for engagement 110 with the annular enlargement 11 and the bowed portion 16 of the spring 14, when the

cap is mounted on the barrel 1, for forcing the spring 14 inwardly which, through the medium of the pin 17 forces the resilient tongue 8 downwardly into the feed duct 5, 5 forming an obstruction for the duct to prevent ink from leaking or oozing out of the duct when the pen is not in use. When the cap 21 is removed from connection with the barrel 1, the resilient feed of the spring 14 10 will cause the bowed portion 16 thereof to spring outwardly, moving the pin 17 outwardly and allowing the resilient tongue 8 to assume its normal position as illustrated in Fig. 1 of the drawing, which allows ink 15 to flow freely through the feed duct 5.

Having thus fully described the invention what is claimed is:

1. In a fountain pen, a feed bar composed of a main body provided with a feed duct, 20 and a resilient tongue forming the upper portion of the wall of said duct, said body provided with lateral enlarged recesses at one end, and lateral extensions formed upon said tongue and engaging in said recesses to 25 prevent longitudinal movement of the tongue.

2. In a fountain pen, a barrel, a feed bar composed of a main body provided with a feed duct, and a resilient tongue forming 30 the upper portion of the wall of said duct, said body provided with lateral enlarged recesses at one end, lateral extensions formed upon said tongue and engaging in said recesses to prevent longitudinal movement of 35 the tongue, a cap, and means carried by said barrel and operated by the mounting of said cap upon the barrel to move the free end of said tongue into a feed duct damming position.

3. In a fountain pen, a barrel, a feed bar carried by said barrel and provided with a feed duct, a resilient tongue carried by said feed bar for movement into said feed duct to dam the same, a flat spring carried by 45 said barrel, a pin carried by said flat spring and engaging said resilient tongue to hold the same in a damming position.

4. In a fountain pen, a barrel, a cap, a feed bar carried by said barrel and provided 50 with a feed duct, a resilient tongue carried by said feed bar for movement into said feed duct to dam the same, a flat spring carried by said barrel for operation by said cap to move said resilient tongue into a damming 55 position when said cap is connected to said barrel.

5. In a fountain pen, a barrel, a feed bar carried by said barrel and comprising a main body provided with a feed duct, and 60 a resilient tongue forming a portion of the wall of said duct, a flat spring carried by said barrel and normally resting in spaced relation to the barrel, a pin carried by said flat spring, a cap, said spring adapted to 65 be forced inwardly upon the connection of

said cap and said barrel whereby said resilient tongue will be displaced by movement of the pin carried by said flat spring to obstruct said feed duct.

6. In a fountain pen, a feed bar provided 70 with a feed duct having its delivery end curving to one side of the bar, a resilient tongue forming a portion of the side of the feed bar toward which the duct curves, the free end of the tongue shaped to snugly fit 75 the curved portion of the wall of said duct to form a dam for the duct upon inward displacement of the tongue, a flat spring, a pin carried by said spring and engaging the free end of said tongue to move the tongue 80 into a damming position upon inward movement of the spring.

7. In a fountain pen, a barrel, a cap, a feed bar provided with a feed duct having 85 its delivery end curving to one side of the bar, a resilient tongue forming a portion of the side of the bar toward which the duct curves, the free end of said tongue shaped to snugly fit the curved portion of the wall of said duct to form a dam for the duct 90 upon inward displacement of the tongue, a flat spring carried by said barrel for operation by said cap to move said resilient tongue into a damming position when the cap is connected to said barrel, means for guiding 95 the movement of said spring, and means for limiting the outward movement of the spring.

8. In a fountain pen, a barrel, a cap, a feed bar carried by said barrel and provided 100 with a feed duct, a resilient tongue carried by the feed bar for movement into the feed duct to dam the same, a flat spring carried by said barrel for operation by said cap to move said resilient tongue into a damming 105 position when said cap is connected to the barrel, means for guiding the movement of said spring, and means to limit the outward movement of the spring.

9. In a fountain pen, a barrel, a cap, a feed bar carried by said barrel and provided 110 with a feed duct having its delivery end curving to one side of the bar, said feed bar provided with a longitudinally extending cut-out portion having lateral enlargements 115 at one end, a resilient tongue seated in said longitudinal cut-out portion and forming a portion of the side of the feed bar toward which the duct curves, lateral extensions formed upon said resilient tongue and seated in said lateral recess enlargements to prevent longitudinal movement of the tongue. 120

10. In a fountain pen, a barrel, a cap, a feed bar carried by said barrel and provided with a feed duct having its delivery end curving to one side of the bar, said feed bar provided with a longitudinally extending cut-out portion having lateral enlargements 125 at one end, a resilient tongue seated in said longitudinal cut-out portion and forming 130

a portion of the side of the feed bar toward which the duct curves, lateral extensions formed upon said resilient tongue and seated in said lateral recess enlargements to prevent longitudinal movement of the tongue, the free end of said tongue shaped to snugly fit the curved portion of the wall of said duct to form a dam for the duct upon inward displacement of the tongue, an enlargement formed upon the delivery end of said barrel, a flat spring carried by said barrel, said enlargement being provided with a recess for receiving an inturned end of said flat spring to guide and limit the movement of the flat spring, a pin carried by said spring and engaging said tongue, said spring adapted to be forced inwardly toward the barrel upon mounting of said cap upon the barrel to force said resilient tongue inwardly into a damming position.

11. In a fountain pen, a barrel, a cap, a feed bar carried by said barrel and provided with a feed duct having its delivery end curving to one side of the bar, said feed bar provided with a longitudinally extending recess in the sides toward which the de-

livery end of said duct curves, a resilient tongue seated in said recess, the free end of said tongue shaped to snugly fit the curved portion of the wall of said duct to form a dam for the duct upon inward displacement of the tongue, an enlargement formed upon the delivery end of said barrel, a flat spring carried by said barrel, said enlargement being provided with a recess for receiving an inturned end of said flat spring to guide and limit the movement of the flat spring, a pin carried by said spring and engaging said tongue, said spring adapted to be forced inwardly toward the barrel upon mounting of said cap upon the barrel to force said resilient tongue inwardly into a damming position.
